UNITED STATES PATENT OFFICE.

SAMUEL R. HARRIS, OF PHILADELPHIA, PENNSYLVANIA.

BOTTLE-CAPPING MACHINE.

SPECIFICATION forming part of Letters Patent No. 787,881, dated April 18, 1905.

Application filed July 5, 1904. Serial No. 215,217.

To all whom it may concern:

Be it known that I, SAMUEL R. HARRIS, a citizen of the United States, residing at the city of Philadelphia, in the county of Philadelphia and State of Pennsylvania, have invented 5 certain new and useful Improvements in Bottle-Capping Machines, of which the following is a specification.

My invention has relation to a machine for 10 pressing to place metallic caps or capsules on bottles through the medium of hydraulic or fluid pressure acting on an elastic cup, into which is placed the neck of the bottle, with the cap loosely mounted thereon; and in such 15 connection my invention has relation in particular to a power-operated machine for effecting such purpose.

The principal objects of my invention are, 20 first, to provide a power-operated machine for fixing metallic caps to bottles which shall be simple, durable, and efficient in operation; second, to provide, in such a machine, two or 25 more elastic cups of different sizes for readily operating on different-sized bottles; third, to provide, in such a machine, means for controlling the pressure on the elastic cups, and, fourth, to provide means for releasing the pressure on either of said elastic cups when 30 not required.

The nature and scope of my present invention will be more fully understood from the 35 following description, taken in connection with the accompanying drawings, forming part hereof, in which—

Figure 1 is a vertical central sectional view 40 of a bottle-capping machine embodying main features of my invention. Fig. 2 is a rear elevational view of the same, certain portions being broken away. Fig. 3 is a side elevational view, on a reduced scale, of the machine and its supporting standards, a portion of the standards being broken away; and Fig. 4 is an enlarged detail view, partly in section and in elevation, of one of the plungers or pistons 45 of the machine and a portion of the guide-rod to which the plunger is attached.

Referring to the drawings, the machine is provided with two or more elastic cups *a* and *b* of different sizes or contours and of the usual 50 construction. These cups *a* and *b* are mount-

ed in chambers *a'* and *b'*, respectively, which chambers are in communication with cylinders or barrels *a²* and *b²*. A plunger or piston *a³* is adapted to be forced into the cylinder *a²* to cause the fluid which is contained 55 within the cylinder *a²* and chamber *a'* to collapse the elastic cup *a* and press to place the cap which rests loosely on the neck of the bottle when inserted in the cup in a well-known manner. A plunger *b³* performs the same 60 function with respect to the cup *b* when the chamber *b'* and cylinder *b²* are filled with fluid. The upper end of the plunger *a³* is secured to a guide-stem *d*, suitably guided in a bearing *d'*, carried by the framework of the machine. 65 A helical spring *d²*, mounted on an extension *d³* of the stem *d*, serves to return the plungers to their uppermost position to relieve the pressure on the elastic cups *a* and *b*. At the lower end of the guide-stem *d* is secured a 70 collar *e*, having extending to the front a projection *e'*, to which the plunger *b³* is secured and by means of which it is operated. Extending toward the rear of the machine from the collar *e* is a projection *e²*, which is adapted 75 to be operated on by a cam *f*, mounted on the shaft *g* of the machine, to force the plungers *a* and *b* downward into their respective cylinders. To cause the guide-stem *d* and the 80 parts carried by the same to come quietly to rest at their uppermost position, there is provided a spring *h*, surrounding the lower end of the extension *d³* of the stem *d* and mounted in a thimble *h'*, carried by the bearing *d'*, 85 which thimble separates the spring *h* from the spring *d²*.

The driving mechanism of the machine is preferably as follows: To one end of the shaft *g* is secured a gear-wheel *g'*, meshing with a pinion *i*, mounted on the counter-shaft *i*. On 90 the other end of the counter-shaft *i* is loosely mounted a driving-pulley *i²*, which is adapted to be locked to the counter-shaft *i* by means of a clutch *i³*. This clutch *i³* is controlled by a foot-treadle *k* through the intervention of a rod *k'*, a bell-crank lever *k²*, and clutch-arm *k³*, acting against the tension of a spring *k⁴*, which normally tends to unlock the pulley *i²* from the shaft *i*. 95

The base *l* of the framework of the machine, 100

as illustrated in Fig. 1, is preferably made hollow to serve as a reservoir for the fluid. A hand-pump l' (shown in Figs. 2 and 3) serves to regulate the degree of pressure required in the capping operation by supplying a greater or less quantity of fluid, as may be desired, from the base l to the chamber a' or b' , with which the pump is connected by means of a suitable pipe m , provided with valves or cocks m' and m'' to control the admission of fluid to the required chamber. To drain either chamber when it is desired to use the other, the chambers a' and b' are connected by a suitable drain-pipe n , provided with valves or cocks n' and n'' to control the egress of the fluid from the required chamber to the hollow reservoir. To permit air to escape or enter when it is desired to fill or empty either of the chambers, the plungers a^3 and b^3 , as shown in Figs. 1 and 4, are provided at their upper ends with air-outlets o , normally closed by means of a screw-valve o' and communicating with a duct o^2 , running through the plungers to their respective cylinders. Having thus described the nature and objects of my invention, what I claim as new, and desire to secure by Letters Patent, is—

1. In a machine of the character described, an elastic cup, a chamber in which the cup is mounted, a cylinder in communication with the chamber, a plunger mounted in the cylinder, a continuously-driven driving mechanism, and means adapted to connect the plunger with said driving mechanism, at the proper time.

2. In a machine of the character described, an elastic cup, a chamber in which the cup is mounted, a cylinder in communication with the chamber, a plunger mounted in the cylinder, a cam adapted to force the plunger into the cylinder, a continuously-driven driving mechanism, and means adapted to connect the cam with said driving mechanism, at the proper time.

3. In a machine of the character described, an elastic cup, a chamber in which the cup is mounted, a cylinder in communication with

the chamber, a plunger mounted in the cylinder, means for filling said chamber a cam adapted to force the plunger into the cylinder, means for operating the cam and a treadle mechanism adapted to control the actuation of said cam.

4. In a machine of the character described, a plurality of elastic cups, chambers in which the cups are respectively mounted, a cylinder communicating with each of the chambers, a plunger mounted in each of the cylinders, and means for filling and draining either chamber and its cylinder, as required.

5. In a machine of the character described, a plurality of elastic cups, chambers in which the cups are mounted, a cylinder communicating with each of the chambers, a plunger mounted in each of the cylinders, a pump controlling the amount of fluid forced into the chamber and its cylinder, and means for draining either chamber and its cylinder.

6. In a machine of the character described, a hollow standard forming a reservoir for fluid, an elastic cup arranged to receive the cap and neck of a bottle, a fluid-chamber surrounding the cup, a pump arranged to force fluid in regulated quantity from the reservoir into the fluid-chamber and a plunger arranged to reciprocate in the fluid-chamber.

7. In a machine of the character described, a hollow standard forming a reservoir for fluid, an elastic cup arranged to receive the neck of a bottle with a cap, a fluid-chamber surrounding the cup, a cylinder connected with said chamber, means adapted to connect said reservoir with said chamber and cylinder, a hollow plunger arranged to reciprocate in said cylinder, and a valve-controlled duct leading from the interior of the plunger to the exterior atmosphere.

In testimony whereof I have hereunto set my signature in the presence of two subscribing witnesses.

SAMUEL R. HARRIS.
